UNITED STATES PATENT OFFICE.

EBER. HUBBARD, OF CHICAGO, ILLINOIS, ASSIGNOR TO THE WILLIMANTIC LINEN COMPANY, OF HARTFORD, CONNECTICUT.

MACHINE FOR MOLDING SPOOLS OR SIMILAR FORMS FROM PULP.

SPECIFICATION forming part of Letters Patent No. 517,924, dated April 10, 1894.

Application filed August 7, 1893. Serial No. 482,571. (No model.)

To all whom it may concern:

Be it known that I, EBER. HUBBARD, a citizen of the United States, residing at Chicago, county of Cook, and State of Illinois, have invented certain new and useful Improvements in Machines for Molding Spools or Similar Forms from Pulp, which are fully set forth in the following specification, reference being had to the accompanying drawings, forming a part thereof.

The purpose of this invention is to provide a mechanism in which articles may be molded from fibrous pulp, the details being particularly designed with reference to molding half spools to be afterward united to form complete spools; but the general features of the invention are applicable to other articles.

In general character the machine is a press, and adapted to be operated by hydraulic pressure, but not absolutely limited to that mode of operation.

In the drawings:—Figure 1 is a front elevation of the press and connected mechanism; the parts being in position of rest preparatory to filling the molds with pulp. Fig. 2 is a side elevation, the position of the parts being the same as in Fig. 1, except that the pulp gates into the mold are closed. Fig. 3 is a vertical section at the line 3—3 on Fig. 2. Fig. 4 is a horizontal section at the line 4—4 on Fig. 2. Fig. 5 is a bottom plan of the bed of the press and mechanism thereon for raising and lowering the molds. Fig. 6 is a detail section at the line 6—6 on Fig. 2. Fig. 7 is a detail section at the line 7—7 on Fig. 2. Fig. 8 is a perspective of a portion of a rib employed in the bottom of the molds to form a furrow in the molded form.

The frame of the press comprises the base 40 A, and upper cap A', corner posts A² A², by which the base and cap are rigidly bound together.

B is the bed which is adapted to reciprocate vertically within the four corner posts, being mounted upon the upper end of the ram of a hydraulic press, whose cylinder A³ is rigid with the base A. The bed B is channeled as shown at b' b', &c., for the purpose of permitting the drainage from it of the water which will be forced out of the pulp by

compression in molding. The bed is covered with a perforated sheet b, said sheet constituting the lower wall of the molds which are mounted upon the bed.

C C C, &c., are molds, all of precisely similar construction, which are located, in any number which the bed may accommodate, upon the upper surface thereof. Twelve such molds are shown in the drawings. The form to be molded in this press is half of a large 55 spool divided longitudinally, so that it has one surface flat except as to the semi-cylindrical groove which is half of the axial aperture through the complete spool. A transverse section, therefore, of each of the molds 60 has precisely the outline of the flat face of the half spool or diametrical section of the spool, and the twelve molds of this character are arranged together in a rectangular group four 65 spools wide and three spools long,—that is, 70 three of said form arranged end to end determining one dimension of the group, and four placed side by side, determining the other dimension. The side walls C' C', &c., of each mold cavity, correspond in horizontal contour 75 to an axial section of the spool.

The spaces c' c', which, by reason of the contour of the molded half spools, are left between them as they lie completed on the bed, permit the easy escape of the water 80 through the perforated cover b thereof into the drainage channels; and thence freely off the bed by whatever course of drainage may be provided. The end walls and partitions between the ends of the several cavities are 85 formed by metal plates C² C², &c., to which the side walls are secured, the whole group of molds being thus rigidly framed together and adapted to be manipulated as a unit. This group of molds is thus adapted to rest upon 90 the bed, and in its vertical movement relatively to the bed is carried accurately by the mechanism for lifting it hereinafter described. To complete the contour of the mold cavity conformably to the shape of the half spool to 95 be molded, half round ribs C⁵, &c., are secured to the upper surface of the bed B,—that is, above the perforated sheet b—in such position that they extend lengthwise through the several mold cavities at the middle point of 100

the bottom of each where the half round groove is to be formed in the half spool. These ribs are longitudinally grooved or fluted, the grooves and intervening ribs being quite fine and being shown in magnified view in Fig. 8. The purpose of this detail of construction will be hereinafter explained.

The height of the mold cavities C is such as to adapt them to contain such a quantity of liquid pulp as will suffice when the water is forced out of it and the pulp reduced to a solid, to form one of the half spools to be molded. In practice, the height will be enough greater than the estimated necessity to allow for the necessary variation in the consistency of the pulp, and the operator will fill the molds to a greater or less depth, according to the consistency of the pulp with which he is operating, being guided by his experience in that respect. To the cap A' of the press frame are secured the stems of the followers Dd Dd Dd Dd, &c., which operate pistonwise in the mold cavities to compress the pulp therein, such followers constituting the upper wall of the mold cavity in that process. The followers present, therefore, on their lower face the precise outline of the curved surface of the half spool, and are perforated to permit the free escape of water upward through them, as they compress the pulp in the mold. Each of these followers is made in two pieces, being divided longitudinally at the middle point, and each piece has an independent stem D', d', respectively, the stem D' being rigidly fastened to the cap, as described, and the stem d' being guided vertically on the stem D', and retained closely in its guide-bearings on that stem, so that the two parts Dd of the follower are inseparable laterally, and have with respect to each other only a slightly vertical movement for a purpose which will hereinafter appear. In detail, the construction is that the stem D' has the lugs D¹⁰ D¹⁰ undercut to form dovetailed slide-bearings for the stem d', which has its edges d¹⁰ d¹⁰ beveled to fit the undercut lugs, and be guided and retained thereby. A spring D², connected at one end to the stem D', and at the other end to the stem d' tends to hold the latter stem up against the stop lug D¹¹ on the stem D', which is the position at which the part d coincides with the part D, to make the complete follower Dd conform to the shape of the half spool. Levers d², respectively fulcrumed upon the stems D' and having offsets d²⁰ which project through those stems d', and engage the margin of the apertures through which they project in the latter stems, are encountered by the mold cases C C respectively, so that when the latter are lifted from the bed, as hereinafter explained, after the bed commences to descend, they operate the levers d², and force downward the parts d of the followers Dd a short distance, with the effect of disengaging the molded half-spoons from the fixed parts of the followers, and because their adhesion

to the other part is not sufficient to retain them, causing them to drop freely onto the bed and be carried down with the farther descent of the latter.

For the purpose of lifting the group of mold cases C C C, &c., from the bed after the compressing is done, I provide four lugs c³ c³, &c., projecting from the outer wall plates of the group of mold cases near the four corners of the group, in such position that they may be connected respectively to the upper ends of vertically reciprocating rods E E E, &c., which are guided vertically in bearings on the bed, and actuated as will now be described. The lower portion of each of these vertically reciprocating rods E E is provided with rack teeth e e, &c., and two shafts e' e' journaled below the bed have each at opposite ends pinions E' E', which engage these racks respectively; to one of these shafts a crank handle c¹⁰ is attached. The rotation of the one shaft having this crank handle is communicated to the other shaft by means of pinions E² E² on the two shafts and horizontal rack-bars E³, guided on the bed and having their rack teeth engaging with the pinions E² E², so that the rotation of one of the shafts e' produces rotation in the same direction of the other shaft e', and the four pinions, one at each end of each of the shafts e', engaging the racks on the rods E E, lift the four corners of the group of molds C C C, &c., simultaneously and equally, a reverse movement of the mechanism tending to lower the group.

For the purpose of charging the mold with liquid pulp, such pulp is conducted through a stand pipe F, in which it is forced by suitable pumping mechanism not shown; and upon each end plate C² of the group of the molds C C C there is fixed a trough C⁴, from the bottom of which a pipe C⁴⁰ extends downward and makes a telescoping connection with the upstanding end of the pipe F; and the end partition walls C² have toward the upper edge, gateways C¹⁰, through which pulp, introduced into the trough through the pipes F and C⁴⁰, may flow into the molds and from mold to mold until all are filled to the required height. These gate-ways are each provided with a sliding gate or valve C¹¹, which are connected together in rows by the rods C¹², whose ends project at opposite ends of the group of molds to permit them to be engaged and operated, and operate the gates. For this purpose, rocking trip bars G G are pivoted at the ends of their lever arms G' G' to the press frame, and adapted, when rocked inward toward the frame, to stand in position to arrest the ends of the rods C¹², as the molds C C descend, and thereby hold the gates up while the descent of the molds is continued, thus opening the gateways. Springs g may be provided, tending to hold the rocking trip bars G in the position described and to throw them back into that position when they are withdrawn. When it is desired to close the valves, as will be done when the molds are

filled with pulp preparatory to compressing, the operator will rock the trip bars outward and the weight of the gates and their connecting rods will cause them all to fall into closed position. Conveniently, the ends of the rods C¹² may be bent up or widened vertically, so that the trip bars G, when thrown out from under the ends of said rods, will be held by the springs g against the ends of the rods, and will not rock inward so as to overhang the latter. When the molds are lifted with the bed as it rises, the trip bars will rock inward under the ends of the rods, and be in position to operate the gates upon the next descent.

In operating this machine, the parts will be first at the position shown in Fig. 1, the bed being at the lowest point, and the molds C C C, &c., resting upon the bed, the followers Dd, &c., being entered into the upper ends of the molds C C, &c., but not below the gateways C¹⁰, which are open, the gates C¹¹ being held up by the trip bars. The depending pipe terminal C⁴⁰ of the trough C will be telescoped into the upstanding end of the pulp supply pipe F, and upon the opening of the pulp-controlling valve F' in such pipe the pulp will flow up into the trough and thence into the several molds until they are filled to the desired height. The valve F' being then closed,—water being admitted to operate the hydraulic ram, the bed rises, carrying up the molds, so that the followers Dd, remaining fixed in position, traverse the mold cavities longitudinally as the latter rise, forcing the water from the pulp through the perforations, both of the sheet b and of the followers, until the followers have reached the bottom of the molds, when the requisite degree of compression will have been obtained if the quantity of pulp admitted has been properly gaged. The operation of the ram now ceasing, the operator will rotate the crank c¹⁰ to lift the mold cases C two or three inches, causing the follower still holding the molded forms on the bed, to emerge from the lower end of the molds, and permit the water then above the follower to drain out. The water will flow off through the perforated sheet b upon the top of the bed and through the grooves in the latter. The bed being now permitted to descend, as soon as it starts down, the operator will further lift the group of molds C C C a little faster than the bed descends, and bring the upper edges of the molds up against the levers d², and thereby force downward the member d of the follower, causing it to push the molded half spools off from the other members D, and cause them to fall onto the bed directly beneath the lower ends of the molds in which they were formed respectively. This movement will be performed preferably before the bed has descended more than just far enough to permit the necessary downward movement of the portion d of the followers, so that the molded forms will not be marred in dropping the short distance to the bed.

As the bed continues to descend the operator will continue to operate the crank and increase the distance between the molds and the bed, although the molds will now be permitted to descend absolutely,—that is, will not be elevated by the rotation of the crank so fast as they are carried down with the bed, but the elevation provided for by the crank-operated mechanism is sufficient to lift the molds above the bed far enough to permit the molded half spools to be removed sideways from the bed preparatory to repeating the operation.

(As a matter of convenience, the sheet b may serve as a tray with which to remove all at once the entire group of half spools produced at each operation,—that is, such sheet need not be fastened to the bed, and a number of such sheets being provided a fresh one may be put in place after such removal, the molded forms remaining upon the sheet upon which they were removed from the press while being further handled, until sufficiently dry to be past danger of bruising.)

By reason of the peculiar character of fibrous pulp I have found that in compressing forms of the shape of these half spools after a certain degree of solidity is obtained by forcing out the moisture, the material not being entirely plastic tends to break apart over the rib which forms the groove in the flat face of the half spool, and many defective spools would ordinarily result from this circumstance. I overcome this tendency and produce spools which are perfect in this respect by means of the longitudinal fluting or grooving of the ribs C⁵. In Fig. 8, this structure is represented in magnified form. In practice, the furrows c⁵ are not deep enough to render unevenness of the surface of the groove greater than can readily be cured in the process of dressing which is necessary in any event. I have made them from one-thirty-second to one-sixteenth of an inch deep, and so far as I have observed, the precise form is not material,—that is, the grooves may be triangular or semi-cylindrical or of any other shape, the requisite being that ridges are left standing upon the semi-cylindrical surface of the ribs C⁵, by which, as I presume, the fibers of partly compacted pulp are detained and prevented from sliding over the inclined surface of the rib during subsequent pressure, as they would otherwise do, with the effect of rupturing the molded form, as above stated.

I claim—

1. In combination with the press frame, the bed adapted to be reciprocated vertically; the mold cases C C C, &c., supported on the bed and adapted to be elevated from it; the followers rigid with the frame, in line respectively with the mold cavities of the mold cases C, and adapted to fit in and traverse the same pistonwise as the bed rises; substantially as set forth.

2. In combination with the press frame, the

- bed adapted to be reciprocated vertically therein; the mold cases supported on the bed, and mechanism for elevating them relatively thereto; the followers secured to the frame and overhanging the bed in line with the cavities of the molds respectively, and adapted to advance pistonwise therein as the molds rise, said followers being composed each of two members, one of which is movable longitudinally; whereby the molded form may be stripped from the follower by such longitudinal movement: substantially as set forth.
3. In combination with the press frame and the bed adapted to be reciprocated vertically therein, the mold cases supported on the bed, the trough C⁴ at one side of the mold cases, said mold cases having gateways near their upper ends through their side and partition walls; whereby the pulp may flow from the trough into the mold cavities; the gates or valves which close such gateways adapted to slide vertically; and the trip bars G on the frame in position to detain the gates while the molds descend and thereby to open the gates: substantially as set forth.
4. In combination with the bed and the mold cases carried thereon, the trough C⁴ having communication with the molds; the supply pipe F, and the depending pipe terminal C⁴⁰, of the trough adapted to telescope with the up-standing end of the supply pipe as the molds descend: substantially as set forth.
5. In combination with a mold for liquid pulp, and a piston follower by which the pulp may be compressed therein; a ridge or elevation in the bottom of the mold cavities to produce a groove or furrow in the molded form, such ridge being provided with slight projec-

tions: substantially as and for the purpose set forth.

6. In combination with the mold C for the half-spool form having a flat bottom with a longitudinal rib; and the follower adapted to operate pistonwise in such mold cavity, the longitudinal rib being longitudinally furrowed, ribbed or fluted: substantially as and for the purpose set forth.

7. In combination with the bed and the molds C C carried thereon, two-part followers Dd, projecting downward into the upper ends of such molds; the lever d² fulcrumed upon one of said parts and operating upon the other, and having one end exposed in the path of the mold, whereby the latter at the upper limit of its movement operates the lever to reciprocate the movable member of the follower: substantially as set forth.

8. In combination with the bed, the molds C C thereon; the uprights E E constituting supports for the group of molds, the shafts 60 journaled in the bed having pinions E', engaging the racks on said uprights, and the pinions E², and the horizontal racks E³, meshing with said pinions E², whereby the rotation of one of said shafts elevates simultaneously all four of the uprights: substantially as set forth.

In testimony whereof I have hereunto set my hand, at Chicago, Illinois, this 24th day of July, A. D. 1893, in the presence of two witnesses.

EBER. HUBBARD.
